UNITED STATES PATENT OFFICE.

JOHN ARNOLD STREUN, OF SHERMAN, TEXAS, ASSIGNOR TO HARDWICKE-ETTER COMPANY, OF SHERMAN, TEXAS.

CLEANER FEEDER FOR COTTON GINS.

Application filed April 25, 1924. Serial No. 708,961.

To all whom it may concern:

Be it known that I, JOHN A. STREUN, a citizen of the United States, residing at Sherman, Texas, have invented a certain 5 new and useful Improvement in Cleaner Feeders for Cotton Gins, of which the following is a specification.

My invention relates to an improvement in cleaner feeders for preparing the cotton 10 for ginning. It is applicable to gins of the ordinary construction and is intended to break up and clean the cotton, and so distribute it that it will be fed evenly to the gin in a clean condition.

15 It is an object of the invention to provide an apparatus for agitating and breaking up the cotton and acting upon the cotton by a draft of air so as to remove the particles of dust and chaff more fully from the cotton 20 before it is fed to the gin.

Another object is to distribute the cotton in an even and uniform flow to the gin. The device shown in the drawing is an improvement upon my prior Patent No. 1,473, 25 059 granted November 6, 1923.

Referring to the drawing herewith Fig. 1 illustrates a vertical section through a cleaner feeder embodying my invention. Fig. 2 is a broken detail illustrating the 30 arrangement of the picket teeth upon the blades of the cylinders. Like numerals of reference refer to like parts in both views.

In feeding cotton to the ordinary gin it is desirable that the ordinary dirt and trash 35 be removed from the cotton and the lumps and balls of seed cotton be broken up and distributed before being passed to the saws of the gin. This results not only in a better ginning of the cotton, but in the production 40 of a cleaner and more valuable staple. The purpose of the present device is to break up and agitate the cotton before it is fed to the gin, and to thoroughly clean the cotton of the particles of dust, sand and trash there- 45 in. In carrying out this purpose, the cotton is discharged to the cleaner by means of a hopper 1 on the upper end of a casing 2. The casing is supported by brackets 3 and 4 upon the upper side of a gin 5.

50 The cotton entering the hopper 1 falls upon two feeding rollers 6 which are mounted upon shafts 7, 7 supported in the sides of the casing 2. These rollers have radial blades 8 and are adapted to rotate 55 in opposite directions as shown in the arrow

in the drawing so as to feed the cotton down between the rollers in a compact bat. These rollers are adjusted to operate at a slow rate of speed so as to allow the agitating members to thoroughly clean the cotton thus fed to them before the cotton goes to the 60 gin.

Below the feed rollers 6 is a cylinder 9 mounted upon a shaft 10 for rotation. This cylinder is constructed of baffles or blades 11 mounted approximately tangential to the shaft 10 as shown in the drawing, and have spacing and reinforcing plates 12 arranged longitudinally of the adjacent blades 11 so as to provide, in effect, a polygonal cylinder 70 with short blades 11 projecting from the angles thereof in the manner shown. The ends of the blades 11 have thereon a series of spaced pins or pickers 13. Said cylinder rotates in the direction of the arrow to carry the cotton removed from the lower end of the bat in a direction toward a cleaner casing 75 to the rear thereof.

Secured upon the rear of the casing 2 is a cleaner casing 20. Mounted rotatably 80 within this casing are a plurality of cleaning cylinders 14 and 15, respectively. The cylinder 14 is mounted upon a shaft 16 to the rear of and slightly below the shaft 10. It is constructed in the same manner as is 85 the cylinder 9, and is adapted to rotate in the same direction. The shafts 10 and 16 are so spaced as to have the teeth 13 upon the blades of the two cylinders interfit as shown in Fig. 2, said teeth being staggered 90 relative to each other so as to allow them to interfit as shown in the drawing.

The cylinder 15 is above and to the rear of the cylinder 14. It is mounted on shaft 17 for rotation in the same direction as the 95 two previously mentioned cylinders. The teeth 13 on the blades interfit with those of the cylinder 14 in the same manner as do those of the cylinders 9 and 14 previously described.

Above the cylinder 14 is an agitating roller 18 mounted for rotation with shaft 19 in a direction opposite to that of the other cylinders. It is constructed as are the cylinders 9, 14 and 15, but is materially smaller 105 and is spaced from the two cylinders 14 and 15 to allow the passage of cotton between said roller and the adjacent cylinders without materially damaging the cotton.

The casing 20 in which the cleaning cyl- 110

inders and the agitating roller are mounted, is shaped to house the cylinders 14 and 15 and the roller 19 fairly closely. The upper portion of the casing is formed into a door 21 hinged at 22 so that it may be lifted to expose the cylinders for cleaning or repair, the door extending to the rear and terminating at 23.

Beyond the door and extending to the lower end of the casing is the sheet iron plate 24 connected to the upper end of the trough 25 in which operates a screw conveyer 26. The said conveyer acts to discharge chaff and dirt through an opening 15 on the side of the casing.

Within the casing is a screen 27 connected with the cross member 28 adjacent the door and spaced uniformly from the outer peripheries of the cylinders so as to surround the three cylinders 9, 14 and 15 on the underside thereof, said screen being attached at its forward end to the supporting member 29 at the mouth of the opening 30 to the chute 31. Between its ends the screen is secured for support to cross bars 32 and 33. Below the screen 27 in the casing 2 is a second screw conveyer 34 acting to discharge the chaff and dirt at the side of the machine.

In the operation of the device, cotton will be fed downwardly between the rollers 6 in a uniform compressed bat against which the teeth 13 on the blades 11 of the cylinder 9 will contact and tear off therefrom small lumps or wads of cotton, throwing it rearwardly upon the cylinder 14. The teeth 13 upon the two cylinders will intermesh in such a manner as to prevent the cotton from being carried around the cylinder 9 and discharged to the gin before it is properly cleaned. The cylinder 14 will engage the cotton carrying it to the rear upon cylinder 15. The blades of the cylinders will act as fans and the cylinders will be rotated at such speed as to cause a material draft of air, tending to throw the cotton outwardly from the cylinders so as to break it up and loosen it so that the dirt may be shaken out of the cotton. The agitator roller 19 will obstruct the free passage of the cotton thrown from the cylinder 14 and will tend to break up the wads or bolls of cotton and distribute it more evenly through the length of the roller. The peripheral speed of the roller 18 will be slightly less than that of the cylinders 14 and 15, and will tend to feed the cotton toward the cylinder 15 in an even flow. The cotton will be carried from the agitating roller 18 over the cylinder 15 against the screen 27 and will thus be carried back against the cylinder 14, and as it passes over the ridge or hump in the screen above the cross piece 32, will be turned over and as it is engaged by the blades of the cylinder 14, will be again

thrown outwardly and the chaff and dirt therein will be blown through the screen toward the lower part of the casing. The casing is open at the sides thereof adjacent the screw conveyer 26 and the chaff and dirt will be scraped and blown from the casing in an obvious manner.

As the cotton passes from the cylinder 14, it will be again turned over and engaged by the blades of the cylinder 9 and thrown to chute 31 to be delivered therefrom to the gin. Dirt and chaff blown through the screen below the cylinder 9 will be carried away through the screw conveyer 34 and the strong draft caused by the rotation of the cylinder 9 will assist in the elimination of the impurities of the cotton.

The forming of the cleaning cylinders in this device in the manner described, results in a more thorough agitation and cleaning of the cotton without material damage to the fibre. The blades of the cylinders act as fans to agitate and break up the cotton and to blow the dirt and chaff from the cotton staple. It has therefore a larger cleaning capacity for the cotton because of the draft of air caused by the rapid rotation of the cylinders, and further through the fact that the cotton being engaged by the blades of the cylinders instead of by spikes such as are employed on ordinary cleaning devices, will not damage the cotton. The action of the agitating roller 18 in combination with the cleaning cylinders in the manner described, results in a cleaner cotton more evenly and smoothly distributed than is customary in the ordinary type of cleaner feeder.

Further objects and advantages will be apparent to one skilled in the art without further description.

What I claim is new and desire to protect by Letters Patent is:

1. A feeder cleaner for cotton gins comprising a casing, feeding rolls rotating to feed cotton downwardly, a combined fan and cleaning cylinder below said rolls, said cylinder comprising a plurality of blades inclined slightly backwardly from the direction of rotation of said cylinder, longitudinal plates between said blades, a plurality of similar cylinders to the rear of said first mentioned cleaning cylinder, an agitating roller above and between said last named cylinders, and screen below said cylinders, said cylinders and roller rotating to carry the cotton rearwardly above said cylinders and back again under them.

2. A feeder cleaner for cotton gins comprising a casing, a hopper, a pair of feeding rollers below said hopper, a series of parallel adjacent cleaning cylinders rotatable in the same direction to carry the cotton over the tops of said cylinders and back beneath the same, an agitating roller adjacent two

of said cleaning cylinders, and rotatable in the opposite direction, said cylinders having inclined toothed blades adapted to create an outward draft of air in rotating, and a screen below said cylinders.

3. In a feeder cleaner for cotton, a casing, a series of cleaner cylinders mounted for rotation in said casing to carry cotton over the tops of said cylinders and back beneath them, an agitator roll cooperating with two of said cylinders to break up and distribute the cotton, said cylinders being polygonal in shape, blades projecting from the angles of said cylinders to agitate said cotton and to create a draft of air in rotating, tending to blow said cotton outwardly from the same and a screen below said cylinders.

4. In a feeder cleaner for cotton gins, the combination with feeder and agitator rolls, of a series of cylinders having rearwardly inclined blades, adapted by rotation, to

agitate the cotton and blow the impurities therefrom, and a screen adjacent said cylinders.

5. In a feeder cleaner for cotton, a series of parallel adjacent cylinders having rearwardly inclined blades thereon, teeth on the outer edges of said blades positioned to interfit on adjacent cylinders during rotation, an agitating roller above said cylinders and cooperating therewith to break up and distribute said cotton.

6. In a feeder cleaner for cotton gins, a rotatable cleaning cylinder comprising a shaft, blades mounted on said shaft tangential therewith, plates secured between said blades away from said shaft to form a polygonal member, and teeth on the outer edges of said blades presented forwardly with said blades in the direction of rotation of said cylinder in the manner described.

JOHN ARNOLD STREUN.
